UNITED STATES PATENT OFFICE.

OSCAR P. OSTERGREN, OF BROOKLYN, NEW YORK, ASSIGNOR TO HARRY REIS, OF WILMINGTON, DELAWARE.

AIRSHIP.

1,000,035.

Specification of Letters Patent. Patented Aug. 8, 1911.

Application filed March 7, 1911. Serial No. 612,803.

To all whom it may concern:

Be it known that I, OSCAR P. OSTERGREN, a subject of the King of Sweden, residing at Brooklyn, in the county of Kings and State of New York, have invented certain new and useful Improvements in Airships, of which the following is a specification.

My invention relates to improvements in air ships, more particularly to an improved air ship of the aeroplane type which combines in its utility that of the hydroplane, the object of the invention therefore being to provide improvements of this character which may be propelled through the air or on the water, which may alight in the water and rise from the water as desired.

A further object is to provide an improved construction and arrangement of planes which operate with equal efficiency to support the ship in the air or to support it on the water.

A further object is to so shape the planes as to tend to cause an automatic equilibrium permitting the center of gravity of the machine to be placed comparatively low and affording a maximum of supporting surface, even when the ship is tilted, causing it to automatically right itself.

A further object is to provide a machine of this character which is designed for carrying a number of passengers, with improved means which may be set to control the lifting capacity of the machine in accordance with the number of passengers.

A further object is to provide improved steering mechanism for a ship of this character which may be utilized for steering the machine in the air or on the water.

With these and other objects in view, the invention consists in certain novel features of construction and combinations and arrangements of parts, as will be more fully hereinafter described and pointed out in the claims.

In the accompanying drawings: Figure 1, is a view in side elevation illustrating my improvements. Fig. 2, is a top plan view. Fig. 3, is a front elevation. Fig. 4, is a rear elevation. Fig. 5, is a view in section on the line 5—5 of Fig. 1. Fig. 6, is a fragmentary

view on an enlarged scale in longitudinal section through the center of the main planes, and Fig. 7, is a diagrammatic view illustrating the position of the machine showing its center of gravity and an angle 55 the machine assumes relative to the horizon.

My improved air ship comprises a fore-and-aft frame 1, which comprises a plurality of longitudinal rods strengthened by horizontal and diagonal braces 2. To the forward end of this fore-and-aft frame, my improved main planes 3 and 4 are secured. This machine is of the biplane type, the upper plane 3 extending in an approximate horizontal line, while the lower plane 4 is 65 of a peculiar shape which will be herein-after described. These planes are connected throughout by vertical and diagonal braces 5 and the fore-and-aft frame 1 is connected to the transverse frame formed by these 70 braces 5 by means of braces 6, as clearly shown in Fig. 2, so as to render the connection a strong and durable one.

By reference particularly to Figs. 3 and 6, the shape of my improved lower plane 4 75 is best seen. This plane, like all the other planes of the machine, comprises two thicknesses of canvas strengthened by ribs and stays, but the intermediate portion of this plane 4 dips downward as shown at 7, 7, 80 providing a central hydroplane 8 adapted to float upon the water. This hydroplane 8 comprises an air chamber which is rendered air tight by treating the canvas with shellac, tar, or other suitable material, and is held 85 open by suitable stays or braces 9. This hydroplane must be of sufficient buoyancy to support the forward heavier portion of the machine on the water. The rear end of the machine is supported on the water by 90 means of a hydroplane 10, which is secured to the rear end of the fore-and-aft frame. It will be noted that these hydroplanes 8 and 10 incline downwardly from front to rear. This insures the forward ends of the 95 planes projecting out of the water, so that if the speed of the propellers be sufficient, the machine will ride off of the surface of the water into the air.

It is to be understood that while I dis- 100

tinguish plane 10 and the central portion of the lower plane 4 by the term "hydroplane" because they operate to support the machine on the water, it is to be understood that 5 these planes also perform the function of aeroplanes, as they, with considerable efficiency, support the machine on the air. In this central depressed portion of the forward end of the machine, a plurality of seats 11 10 are located, the central one being for the aviator, and the outside ones for passengers.

It is to be understood that the machine is not limited to any particular number of seats for passengers, but three will illustrate 15 the principles of the invention. To regulate the balance of the machine in accordance with the number of passengers, a balancing plane 12 is positioned horizontally and supported in a frame 13 projecting above the 20 rear end of the fore-and-aft frame 1. The idea of this plane is to regulate the lifting force at the rear end of the machine, so as to keep the machine on a horizontal keel fore-and-aft. If the weight is heavier in front, 25 it is desirable to change the angle of this plane 12, so that it will have less lifting force at the rear end, otherwise, the rear end of the machine would rise higher than the forward end, and tend to tilt.

30 Suitable means may be provided for locking this plane at various angles, and I have illustrated a simple means for that purpose which consists of a rod 14 connected to a crank arm 15 on the plane 12, and provided 35 with three openings 16, any of which are adapted to receive a pin 17 on frame 1. This number of openings is supposed to illustrate the number of adjustments, as there are accommodations for three passengers, but this 40 precise adjusting means is not essential, and I do not restrict my invention thereto.

In the center of the machine, at its forward end, a suitable engine 18 is located and drives propellers 19, the propellers being 45 driven by the same engine in opposite directions, and one propeller positioned a quarter turn ahead of the other, so that the propellers may revolve in the closest possible proximity and obtain the maximum pressure on 50 the air.

To steer the machine vertically, a horizontally positioned steering plane 20 is pivotally supported on a frame 21 at the rear end of frame 1, and may be controlled by 55 various means. I have illustrated a simple mechanism for the purpose, which consists of a rod 22 which connects a crank arm 23 on plane 20 with a lever 24 located adjacent the aviator's seat 11. To steer the machine 60 horizontally, I provide at the rear and central portion of the fore-and-aft frame, a vertically positioned steering plane 25. This plane 25 is fixed to turn with a vertical shaft 26, the latter guided in a sleeve 27, which

projects through the hydroplane 10. On the 65 lower end of this shaft 25, a fork 28 is secured, and in said fork a wheel 29 is mounted. This wheel 29, together with wheels 30 supported in frames 31 at the forward end of the machine, serve to support 70 the machine on the ground, and roll over the ground as the machine begins its flight. The rear wheel 29, however, has the additional function of a rudder when the machine is on the water, because the movement of plane 25 75 gives a corresponding movement to the wheel 29, and the latter is therefore positioned at an angle in the water to steer the machine. In addition to this plane 25 for steering the machine horizontally or to left 80 and right, vertical parallel planes 32 are pivotally supported on posts 33 at the forward end of the machine. These planes 32 are connected by a rod 34, which compels them to move in unison. 85

35, is an operating lever which is fulcrumed between its ends on a bracket 36 secured to one of the stays of the machine, and the lower handle end of this lever is located adjacent the aviator's seat. The 90 upper end of this lever 35 is connected by a rod 37 with a crank arm 38 on plane 25, and said rod 37 is also connected by a link 39 with a crank arm 40 on one of the planes 32. It will therefore be noted that when lever 35 95 is moved, the three planes 32, 32, and 25 will be simultaneously turned at an angle to steer the machine to right or left. The particular mechanism for simultaneously moving these planes may, of course, be varied without departing from the invention.

By constructing my improved machine on the lines illustrated and described, I believe I attain a maximum of automatic equilibrium by reason of the fact that at all ordinary angles, the planes may assume, they will have a large bearing surface on the air, which tends to right the machine, and I am enabled to position the center of gravity low, as shown at 41 in the diagrammatic view Fig. 7. In this view, the line 42 represents the horizon, and the line 43 the normal line that the machine should assume. In full lines, the machine is shown at an angle such as it might frequently assume, due to 105 treacherous air currents.

Following the vertical line 44 through the center of gravity, it will be noted that that portion of the machine to the left or the lower portion, has an air support far in excess of 110 that of the other side of the machine, thus tending to lift that side of the machine and right it. The shape of the lower plane 4 in the angle illustrated at 45, and the end illustrated at 46, grips onto the air and tends to 115 throw this lower end upwardly. This angular relation of the planes with the horizon, and their supporting qualities on the

air permits the relatively low position of the center of gravity, which is desirable in a machine of this character. The several planes of the machine are preferably strengthened by truss wires 47, and posts 48 as shown.

In operation, we will assume the machine to be on the ground. When the engine is started, the machine begins to move along 10 the ground rolling upon the wheels 29 and 30, until the propellers turn with sufficient force for the planes to ride on the air and lift the machine. During the flight in the air, the machine is steered vertically and 15 horizontally by means of the levers 35 and 24, and the plane 12 is positioned at the proper angle in accordance with the number of passengers in the machine. If the machine alights on the water, the hydroplanes 20 8 and 16 will support the same, and if the speed of the propellers increase sufficiently, the machine will lift out of the water by reason of the incline of the hydroplanes. While in the water, the movement of lever 25 35 causes the wheel 29 to move angularly and act as a rudder for the machine.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. In a machine of the character described, the combination with a fore-and-aft frame, 40 of upper and lower transverse planes at the forward end of said frame, said lower plane depressed at its intermediate portion, said depressed portion hollow and constituting a hydroplane, substantially as described.

2. In a machine of the character described, the combination with a fore-and-aft frame, of upper and lower transverse planes at the forward end of said frame, and said lower plane depressed at its intermediate portion, 50 said depressed portion hollow and constituting a hydroplane, said hydroplane positioned at an angle from front to rear with its forward end highest, substantially as described.

3. In a machine of the character described, the combination with a fore-and-aft frame, of upper and lower transverse planes at the forward end of said frame, and said lower plane depressed at its intermediate portion, 60 said depressed portion hollow and constituting a hydroplane, and a pivoted balancing plane at the rear end of said frame, substantially as described.

4. In a machine of the character described,

the combination with a fore-and-aft frame, 65 of upper and lower transverse planes at the forward end of said frame, and said lower plane depressed at its intermediate portion, said depressed portion hollow and constituting a hydroplane, said hydroplane positioned at an angle from front to rear with its forward end highest, and a pivoted balancing plane at the rear end of said frame, 70 substantially as described.

5. In a machine of the character described, 75 the combination with a fore-and-aft frame, of upper and lower transverse planes at the forward end of said frame, and said lower plane depressed at its intermediate portion and in a plane substantially parallel with the end portions of said lower plane, a vertical shaft at the rear end of the frame, a steering plane on said shaft, supporting wheels on the front end of the frame, and a steering wheel secured on the 80 lower end of said shaft and adapted to turn angularly therewith, substantially as described.

6. In a machine of the character described, 85 the combination with a fore-and-aft frame, of upper and lower transverse planes at the forward end of said frame, said lower plane depressed at its intermediate portion, said depressed portion hollow and constituting a hydroplane, a vertical shaft at the 90 rear end of the frame, a steering plane on said shaft, supporting wheels on the front end of the frame, and a steering wheel secured on the lower end of said shaft and adapted to turn angularly therewith, substantially as described.

7. In a machine of the character described, 95 the combination with a fore-and-aft frame, of upper and lower transverse planes at the forward end of said frame, and said lower plane depressed at its intermediate portion, said depressed portion hollow and constituting a hydroplane, said hydroplane positioned at an angle from front to rear with its forward end highest, a vertical 100 shaft at the rear end of the frame, a steering plane on said shaft, supporting wheels on the front end of the frame, and a steering wheel secured on the lower end of said shaft and adapted to turn angularly therewith, substantially as described.

8. In a machine of the character described, 105 the combination with a fore-and-aft frame, of upper and lower transverse planes at the forward end of said frame, and said lower plane depressed at its intermediate portion and in a plane substantially parallel with the end portions of said lower plane, and a pivoted balancing plane at the rear end of said frame, a vertical shaft at the 110 rear end of the frame, a steering plane on said shaft, supporting wheels on the front end of the frame, and a steering wheel secured on the lower end of said shaft and adapted to turn angularly therewith, substantially as described.

cured on the lower end of said shaft and adapted to turn angularly therewith, substantially as described.

9. In a machine of the character described, the combination with a fore-and-aft frame, of upper and lower transverse planes at the forward end of said frame, and said lower plane depressed at its intermediate portion, said depressed portion hollow and constituting a hydroplane, a pivoted balancing plane at the rear end of said frame, a vertical shaft at the rear end of the frame, a steering plane on said shaft, supporting wheels on the front end of the frame, and a steering wheel secured on the lower end of said shaft and adapted to turn angularly therewith, substantially as described.

10. In a machine of the character described, the combination with a fore-and-aft frame, of upper and lower transverse planes at the forward end of said frame, and said lower plane depressed at its intermediate portion, said depressed portion hollow and constituting a hydroplane, said hydroplane positioned at an angle from front to rear with its forward end highest, a pivoted balancing plane at the rear end of said frame, a vertical shaft at the rear end of the frame, a steering plane on said shaft, supporting wheels on the front end of the frame, and a steering wheel secured on the lower end of said shaft and adapted to turn angularly therewith, substantially as described.

35 11. In a machine of the character described, the combination with a fore-and-aft frame, of transverse planes secured to the forward end of said fore-and-aft frame, a transverse plane fixed to the rear end of said fore-and-aft frame, a balancing plane supported above the upper portion of the fore-and-aft frame at its rear end, and means for locking said balancing plane at various angular positions relative to the frame, substantially as described.

12. In a machine of the character described, the combination with a fore-and-aft frame, of transverse planes secured to the forward end of said fore-and-aft frame, a transverse plane fixed to the rear end of said fore-and-aft frame, a balancing plane supported above the upper portion of the fore-and-aft frame at its rear end, a crank arm on said balancing plane, a rod connected to said crank arm and having a plurality of openings therein, and a pin on said frame adapted to enter any of said openings, substantially as described.

13. In a flying machine, the combination with a fore-and-aft frame, transverse main planes secured to said frame at its forward end, diagonal stays and braces connecting said frame and planes, vertical rods connecting said planes, two vertically positioned

steering planes on said last-mentioned rods, 65 means connecting said steering planes to compel them to move together, a vertically positioned steering plane at the rear end of said frame, and means coöperatively connecting all of said steering planes compelling 70 their simultaneous operation, substantially as described.

14. In a flying machine, the combination with a fore-and-aft frame, transverse main planes secured to said frame at its forward 75 end, diagonal stays and braces connecting said frame and planes, vertical rods connecting said planes, two vertically positioned steering planes on said last-mentioned rods, means connecting said steering planes to 80 compel them to move together, a vertically positioned steering plane at the rear end of said frame, means coöperatively connecting all of said steering planes compelling 85 their simultaneous operation, a plurality of 90 seats on the lower main plane, a horizontally positioned steering plane at the rear end of said frame, and means adjacent one of said seats for moving said planes, substantially as described.

15. In a flying machine, the combination with a fore-and-aft frame, transverse main planes secured to said frame at its forward end, diagonal stays and braces connecting said frame and planes, vertical rods connecting said planes, two vertically positioned steering planes on said last-mentioned rods, means connecting said steering planes to 95 compel them to move together, a vertically positioned steering plane at the rear end of said frame, means coöperatively connecting all of said steering planes compelling 100 their simultaneous operation, a plurality of seats on the lower main plane, a horizontally positioned steering plane at the rear end of said frame, means adjacent one of said seats for moving said planes, a pivoted balancing 105 plane at the rear end of said fore-and-aft frame, and means for locking said balancing plane at various angles in accordance with 110 the number of passengers in the machine, substantially as described.

16. In a machine of the character described, the combination with a fore-and-aft frame, an upper main plane secured on 115 said fore-and-aft frame, extending in a horizontal line transversely, of a lower main plane positioned below the upper main plane, with its end portions and its intermediate portion positioned parallel with 120 the upper plane, the intermediate portion being at a lower elevation than the end portions and in a plane substantially parallel with the end portions of said lower plane, and inclined portions connecting the two 125 elevations of the lower plane, substantially as described.

17. In a machine of the character de-

scribed, the combination with a fore-and-aft frame, an upper main plane secured on said fore-and-aft frame, extending in a horizontal line transversely, of a lower main plane positioned below the upper main plane, with its end portions and its intermediate portion positioned parallel with the upper plane, the intermediate portion being at a lower elevation than the end portions, inclined portions connecting the two elevations of the lower plane, said lowest

portion of the lower plane inclined downwardly from front to rear and constituting a hollow air chamber, substantially as described.

15

In testimony whereof I have signed my name to this specification in the presence of two subscribing witnesses.
